[57] CLAIM

The ornamental design for a tackle container, as shown and described.

DESCRIPTION

FIG. 1 is a top plan view of a tackle container showing our new design, with the lid shown in the closed position;
FIG. 2 is a bottom plan view thereof;
FIG. 3 is a front elevational view thereof;
FIG. 4 is a left side elevational view thereof;
FIG. 5 is a right side elevational view, with the lid shown in an open position;
FIG. 6 is a top plan view thereof;
FIG. 7 is a perspective view thereof; and,
FIG. 8 is a perspective view of an alternate embodiment shown with the lid open, identical to the embodiment of FIGS. 1-7 except further including an extra inner compartment.
